CONTAINER FOR LIQUID PRODUCTS

Norman J. Huber, Mount Lebanon, Pa., assignor to
 United States Steel Corporation, a corporation of
 Delaware

Filed Dec. 12, 1967, Ser. No. 9,749

Term of patent 14 years

Int. Cl. D9—03

U.S. Cl. D9—175

FIGURE 1 is a top plan view of a container for liquid products embodying my new design;

FIGURE 2 is an elevational view;

FIGURE 3 is a perspective view;

FIGURE 4 is a fragmentary sectional view taken on the line IV—IV of FIGURE 1; and

FIGURE 5 is a sectional view taken on the line V—V of FIGURE 1.

I claim:

The ornamental design for a container for liquid products, as shown.
